UNITED STATES PATENT OFFICE.

EDWARD POSSON, OF CHICAGO, ILLINOIS.

VENTILATOR FOR REFRIGERATOR-CARS.

1,218,896.

Specification of Letters Patent. Patented Mar. 13, 1917.

Application filed February 5, 1912. Serial No. 675,611.

To all whom it may concern:

Be it known that I, EDWARD POSSON, a citizen of the United States, residing at Chicago, in the county of Cook and State of Illinois, have invented certain new and useful Improvements in Ventilators for Refrigerator-Cars, of which the following is a specification.

My invention relates in general to freight cars, and more particularly to ventilators for refrigerator cars.

It is necessary that refrigerator cars should be provided with ventilators in order that perishable freight, such as fruit, may be supplied with fresh air during transportation. It is desirable that the amount of fresh air should be varied according to the weather conditions and according to the character and condition of the perishable freight. It is also desirable that the ventilator should be of such construction as to permit complete heat insulation of the car walls, essential to refrigerator cars.

My invention has for its objects to provide a ventilator for refrigerator cars which may be readily adjusted to regulate the supply of fresh air; which will prevent the ingress of cinders, dust and water, and which will permit the complete insulation of the car walls.

A further object of my invention is to provide a ventilator for freight cars which will be simple in construction, convenient in operation, and efficient in use.

My invention will be more fully described hereinafter with reference to the accompanying drawings, in which the same is illustrated as embodied in a convenient and practical form, and in which—

Figure 1 is a plan view of one end of a refrigerator freight car equipped with my improved ventilator;

Fig. 2, an end view, one-half in elevation and the other half in vertical section, along the line 2 2, Fig. 1;

Fig. 3, a horizontal sectional view along the line 3 3, Fig. 4;

Fig. 4, a vertical sectional view on the line 4 4, Fig. 1, the ventilator being shown closed;

Fig. 5, an enlarged sectional view similar to Fig. 4, showing the ventilator fully open.

The same reference characters are used to designate the same parts in the several figures of the drawings.

Reference character A indicates the roof

of a refrigerator freight car having at one end a raised platform b through which extend hatchways to the ice-box B within the end of the car. The hatchways are closed by hatches B', B² of any suitable construction. The platform b serves to support the operator while delivering ice through the hatchways to the ice-box within the car. a indicates the usual runway extending along the longitudinal center of the car roof. b' designates the usual brake staff journaled vertically upon the end of the car.

A', A² indicate the vertical side posts at the corners of the car wall, while A³ designates the vertical center post. A⁴ indicates the end sill which extends transversely of the car and is secured to the upper ends of the side and center posts. The end sill, as shown in Figs. 4 and 5, is set back from the end of the car substantially the thickness of the center and side posts, but the side plates a' and a² (see Fig. 3) extend to the end of the car and overlap the side posts. Located below the end sill A⁴ and extending across the upper end of the car is a beam C, the outer surface of such beam being substantially flush with the inner surfaces of the center and side posts, as shown in Fig. 3. A second beam A⁵, comprising aligned sections extending on opposite sides of the center posts to the end posts, is located slightly below the beam C and is provided with a downwardly and outwardly inclined upper surface. Located above the inner portion of the transverse beam C is a transverse partition c, the latter being spaced apart at its lower edge from the upper surface of the beam C so as to form openings C' and C² extending into the ice-box B. Vertical sliding doors D' and D² control the openings C' and C² and are mounted in suitable guides above the outer portion of the beam C. When the doors D' and D² are in their lower closed position their upper edges overlap and closely engage the outer lower edge of the partition c, while the lower edges of such doors are outwardly and downwardly beveled and fit within corresponding seats, such as c', formed in the outer portion of the upper surface of the beam C.

A metallic plate E extends across the end of the car above the beam A⁵ and overlying the outer surfaces of the end posts A' and A² and center post A³. The upper edge of the plate E is bent inwardly, as shown at e, beneath the portion of the platform b which

overlies the beam A^5 . The inner edge of the inner projecting portion e of the plate E is bent around a transverse filler a^4 overlying the end sill A^4 . The lower edge of the plate E is deflected outwardly, as shown at e^2 , so as to form an opening between the lower edge of the plate E and the adjacent edge of the sheathing secured to the transverse beam A^5 . A deflector e^3 extends from the inner surface of the plate E adjacent its lower edge, such deflector being inclined downwardly and inwardly and terminating at its lower edge a short distance away from the adjacent surface of the beam A^5 .

15 Located within the upper portion of the space above each section of the beam A^5 is a plate E' which is inclined downwardly and inwardly from the inner surface of the plate E at the top thereof into contact with the end sill A^4 against which the plate E' is secured. The plate E' continues downwardly to a point substantially opposite the lower edge of the partition c where it terminates in an outwardly extending inclined 20 flange e' . The plate E' , together with the outer surface of the partition c , serves as a guideway for the sliding doors D' and D^2 .

The plate E is provided along its upper portion with elongated openings F' and F^2 30 extending substantially the entire width of the top of the car. Around the openings F' and F^2 the plate E is bent to form flanges to which are secured screens f' , f^2 completely closing the openings F' and F^2 . 35 Vertically sliding metallic doors G' and G^2 are located in contact with the inner surface of the plate E and are adapted to close the openings F' and F^2 , respectively.

40 A shaft H extends transversely within the space between the transverse beam A^5 and plate E' at a plane substantially at the horizontal center of such space. The shaft H extends through the center post A^3 and each end is supported in a bracket, such as 45 H' , secured to the filler adjacent the corresponding end post, as clearly shown in Fig. 2. Similar brackets, such as H^2 , are secured to the fillers at the opposite sides of the center post A^3 and serve to support the shaft H . Fixed upon the portion of the shaft H between the center post A^3 and side post A^2 are gear wheels K' , K^2 , while 50 gear wheels K^2 , K^2 are secured upon the portion of the shaft H between the center post A^3 and side post A^1 . The gear wheels are located within the respective brackets H' and H^2 , as shown in Fig. 4.

Extending upwardly from ears d at the 60 lower edges of the doors D' and D^2 are pairs of rack bars d' and d^2 , the pair of rack bars d' being pivotally connected to the ears d adjacent the lower edges of the door D' , while the pair of rack bars d^2 , d^2 are 65 pivotally connected to the ears d adjacent the lower edge of the door D^2 . The rack

bars d' , d' extend upwardly and mesh with the gear wheels K' , K' , while the pair of rack bars d^2 , d^2 extend upwardly and mesh with the pair of gears K^2 , K^2 . The brackets H' and H^2 serve to retain the rack bars 70 in mesh with the corresponding gear wheels, as clearly shown in Fig. 4.

Depending from the vertically sliding metallic door G' are rack bars g' , g' pivotally connected at their upper ends to ears g secured adjacent the lower edge of the door. These rack bars mesh with the gears K' , K' on the opposite peripheries thereof from the rack bars d' , d' . Similar rack bars g^2 , g^2 are pivotally secured at their 80 upper ends to ears g secured to the lower edges of the door G' and meshing with the gears K^2 , K^2 at the opposite sides of their peripheries from the rack bars d^2 , d^2 .

A bevel gear L is fixed upon the shaft H 85 and meshes with a bevel gear M fixed upon the lower end of a vertical shaft m , as clearly shown in Fig. 2. l indicates a bracket secured to a vertical member of the car framework provided with angular portion through which the shafts H and m extend and which serves to retain the bevel gears L and M in mesh. The upper end of the shaft m extends through a plate O secured on the upper surface of the platform 90 b adjacent the front edge thereof, as shown in Fig. 1. The plate O is provided with a series of spaced lugs o' , any one of which may be engaged by an opening n' formed in the handle N pivoted at its inner bifurcated end upon the upper end of the 95 shaft m .

The manner of use and operation of my improved ventilator is as follows: When it is desired to admit air to the interior of the 100 car, the handle N is swung upwardly so as to disengage the opening n' therein from the engaged lug o' on the plate O , after which the handle N is rotated, thereby rotating the shaft m and through the meshed bevel gears 105 M and L rotating the shaft H . The rotation of the shaft H through the engagement of the gears thereon with the respective pairs of rack bars serves to lower the doors G' and G^2 and to raise the doors D' and D^2 , 110 thereby uncovering the openings F' and F^2 in the plate E downwardly from their upper edges and simultaneously uncovering the openings C' and C^2 below the partition C upwardly from their lower edges. By 115 rotating the handle N to any desired extent, the doors G' and G^2 and D' and D^2 may be opened more or less according to the amount of fresh air which it may be desired to supply to the car. After the handle N has been 120 rotated sufficiently to effect the desired opening of the doors, it is swung downwardly so that its recess n' will engage the nearest lug o' , thereby locking the shaft m against further rotation and through the meshed bevel 125 gears M and L locking the shaft H . The 130

gears and meshed gears and rack bars, retaining the doors in the positions to which they have been adjusted.

It will be observed that the doors D' and 5 D² can only open to an extent corresponding to the degree of opening the doors G' and G². Hence only so much of the screened openings F', F² are uncovered as is necessary to supply the requisite amount of fresh air 10 to the openings C' and C².

Any water which may pass through the uncovered portions of the screened openings F' and F² is deflected by the plate E' and runs downwardly along the surface of 15 the vertical portion of said plate until the outwardly inclined flange e' at the lower edge of said plate is reached from which the water drops clear of the doors D' and D² upon the downwardly inclined surface of 20 the beam A⁵ from which the water passes through the opening below the edge of the deflector e³ and out of the opening covered by the offset portion e² at the lower edge of 25 the plate E. The deflector e³ serves to direct the air which has passed downwardly within the space F toward the openings C' and C².

The air space formed between the plates E and E' not only serves as a conduit 30 through which the air passes from the screened openings F' and F² to the openings C' and C², but when the doors are closed, such air space openings serve to contain an insulating volume of air. The provision 35 of my improved ventilator, therefore, does not interfere with the complete insulation of the walls of a refrigerator car, inasmuch as the air chamber F is located immediately above the usual insulation containing space 40 between the inner and outer sheathing of the car walls.

From the foregoing description, it will be observed that I have invented an improved construction of ventilator for freight cars 45 which may be conveniently adjusted to control the volume of air supplied to the interior of the car; which permits the complete insulation of the walls of the car, and which prevents the ingress of dust, cinders 50 or water when open.

While I have described more or less in detail the specific form in which I have illustrated my invention as embodied, yet I do not wish to be understood as limiting myself thereto, as I contemplate changes in 55

form, proportion of parts, and substitution of equivalents, as circumstances may require, or as may be deemed expedient.

I claim:

1. A car having spaced apart walls at one 60 end thereof, said walls being each provided with ventilating openings, said openings being offset the one with respect to the other, and means to simultaneously open and close said openings. 65

2. A car having an end wall provided with an opening therein, a plate spaced from said end wall, said plate being provided with an opening offset with respect to said first named opening, a closure for said opening in said plate, and means to operate said closure, said plate being arranged to provide an aperture adjacent its lower portion, said plate being further provided with a strip secured thereto and inclined with 70 respect to said plate, said strip being located adjacent said aperture.

3. A car having an end wall provided with an opening therein, a plate spaced from said end wall, said plate being provided with an opening offset with respect to said first named opening, a closure for said opening in said plate, means to operate said closure, said plate being arranged to provide an aperture adjacent its lower portion, said 80 plate being further provided with a strip secured thereto and inclined with respect to said plate, said strip being located adjacent said aperture, and means to direct water, dust and the like outwardly beneath 90 said strip through said aperture.

4. A car having an end wall provided with an air chamber therein, the opposite vertical walls of said air chamber being provided with offset openings, the lower 95 wall of said air chamber being formed by a transverse beam having a downwardly and outwardly inclined upper surface, and the outer wall of said air chamber being formed by a plate which terminates along its lower 100 edge adjacent to but spaced from said transverse beam whereby a drain opening is provided for said air chamber.

In testimony whereof, I have subscribed my name.

EDWARD POSSON.
